(57) **CLAIM**

The ornamental design for a consumer product bottle, as shown and described.

DESCRIPTION

FIG. 1 is a front perspective view of a consumer product bottle showing the new design;

FIG. 2 is a front perspective view of the consumer product bottle rotated relative to FIG. 1;

FIG. 3 is a rear perspective view of the consumer product bottle;

FIG. 4 is a rear perspective view of the consumer product bottle rotated relative to FIG. 3;

FIG. 5 is a front view of the consumer product bottle;

FIG. 6 is a rear view of the consumer product bottle;

FIG. 7 is a side view of the consumer product bottle;

FIG. 8 is an opposing side view of the consumer product bottle;

FIG. 9 is a top view of the consumer product bottle; and,

FIG. 10 is a bottom view of the consumer product bottle. The broken lines shown herein depict environmental subject matter only, and form no part of the claimed design.
